UNITED STATES PATENT OFFICE.

JOHN S. METCALF, OF INDIANAPOLIS, INDIANA.

GRAIN-SHOVEL MECHANISM.

SPECIFICATION forming part of Letters Patent No. 278,993, dated June 5, 1883.

Application filed April 25, 1883. (No model.)

To all whom it may concern:

Be it known that I, JOHN S. METCALF, of Indianapolis, Indiana, have invented a new and useful Improvement in Grain-Shovel Mechanism, of which the following is a description, reference being made to the accompanying drawings, in the several figures of which like letters indicate like parts.

My invention relates to apparatus, automatic in its action, by which a grain-shovel is operated in unloading cars, and will be understood by any one skilled in such matters from the following description.

In the drawings, Figure 1 represents a front view of my machine; Fig. 2, a top view; Fig. 3, an end view; Fig. 4, a cross-section view on the line xx , Fig. 1; Fig. 5, a cross-section view on the line yy , Fig. 1; Fig. 6, a longitudinal section of the spool Sp and its screw S and the adjacent parts, showing the main shaft Ms in its place; Fig. 7, a side view of the two parts of the clutch and the steel face Sp' ; Fig. 8, an end view of one of the jaws of the clutch; Fig. 9, a side view of the tripping-lever tl and latch l . Fig. 10 is an end view of the same.

In detail, Ms is the main shaft, supported from the frame F by the hangers h and h' , the latter being shown in horizontal section in Fig. 1, and having an outside cover-box, hb , recessed at one end to admit the flange of the collar co , which thus secures the spool in the same relative position to the frame. By reference to Fig. 6 it will be seen that this collar co , the spool Sp , and screw S are all one piece of metal, revolving upon the main shaft.

The yoke-arm ya , Fig. 3, is hinged in the rear to the frame by the hinge hg , and, passing over the spool, is loosely connected with the frame F in front by a set-screw, ss , and jam-nut, thus allowing a vertical movement or play between guide-flanges j , raised from the plate F of the frame. This set-screw thus regulates the up-and-down movement of the yoke-arm ya , and consequently determines the bearing or friction of the cam-sector ee' upon the face of the friction-wheel. In the top of this yoke-arm ya an opening is made to admit the T end, Fig. 5, of the tripping weighted arm ta , and bearings are formed in the sides of this opening for a shaft, p , which passes through the T and through an eye formed on the end of the cam-sector ee' , which

is arranged to press closely upon the face of the friction-wheel fw . Its movement is indicated by the dotted lines in Fig. 4.

In Fig. 5 is shown the detail of the construction of the T of the tripping-arm ta . A radial slot, rs , is formed on the inside of the opening of the T , and a feather is inserted in the shaft p , so that the part T , when it has rotated the length of the slot, will lift the weight W' from its rest 3 , Fig. 4, and bring it nearly to an upright position, as shown in Fig. 3. A projection, 1 , is formed on the T and another, 2 , on the yoke-arm, to limit the forward movement of the weighted arm ta . This movement is effected by that of the cam, both being mounted on the same shaft, p .

The friction-wheel fw is bolted to the spool Sp , as shown in Fig. 6. N is a nut, which travels back and forth on screw S , having pushers p' on either side, Fig. 6, and a bar on the top, b , Fig. 2, the ends of which rest and slide on frame-plates F and prevent the revolution of the nut. The ends of the pushers have coiled springs attached, which operate to push away and disengage the opposite clutch, c . This clutch has a circumferential groove in its periphery to receive the edge of the shifting-lever Sl . A curved arm, ca , bolted to the plates F by its short end, provides a support and bearing for a pivot, 4 , that passes through the upper part of the shifting-lever, which here is branched—one, and the shorter arm, extending upward, to engage in a notch in the tripping-lever tl ; and the other, the longer arm, extends to the rear and carries a counter-balance, W . The tripping-lever tl swings on a pivot, 5 , in bearings in the upper end of the curved arm ca , and has a latch, l , pointed oval shape, pivoted to its forward end, which is adapted to engage with an oval-shaped latch-pin, lp , fixed on the side of the cam, so that the latch-pin will slip under the latch on its backward and over it in its forward movement.

The letters ee' indicate the clutches, and Sp' is a steel face for receiving the impact of the clutch, and is secured, as shown in Fig. 7, by a screw passing through the clutch, the diagonal arm of the steel face Sp' , and into the clutch-beyond, the screw being driven parallel with the steel face Sp' , and it is thus prevented from being loosened by the blow, as is the case when it is driven through the steel face itself.

The rope r is wound upon the spool and the shovel is fastened to its outer end.

My device operates as follows: If the rope r be pulled by the operator after power has been applied to the main shaft, the rope unwinds, the spool revolves, carrying with it the friction-wheel Fw , the screw S , and the clutch c . This movement causes the nut N to move on the screw S toward the friction-wheel Fw , carrying with it the pushers p' and bar b , which, as the nut approaches nearest the friction-wheel, take the positions indicated by the dotted lines in Fig. 2. Whenever the operator ceases to pull upon the rope the counter-balance W' begins to assert itself. It falls backward, carrying the sector ec forward, and its grip upon the friction-wheel moves the spool forward until the latch-pin lp engages with and passes over the latch, depressing it, and thereby raising the opposite end of the tripping-lever tl , disengaging it from the short arm of the shifting-lever, allowing the weight W to fall, and operating to rush the clutch c forward on the main shaft and engage with the clutch c' on the spool. This turns the spool forward and winds up the rope, the nut N returns on the screw S until the pushers touch the lever Sl and disengage the clutches. The tripping-lever tl hooks on again to the arm of the shifting-lever Sl , and the machine is ready for another operation.

It will be understood of course that the clutch c revolves with the main shaft and slides on a feather, K , inserted in the shaft. A little stop, sp , Fig. 2, is fixed on the side of the friction-wheel Fw to prevent the nut N from coming in contact with the friction-wheel. A set-screw, ss' , is used to secure the sector ec to the shaft p .

What I claim, and desire to secure by Letters Patent, is the following:

1. In a clutch mechanism, the hinged yoke-arm ya , having an opening at the top to receive the T -arm of the weighted lever ta , the latter mounted on a shaft passing through bearings in the yoke-arm, which shaft also supports a cam-sector, ec , in combination with such cam, a friction-wheel adapted to engage with it, and a supporting-frame, substantially as described.

2. In a clutch mechanism, the combination of the spool Sp , the collar co , screw S , clutch c' , all formed in one piece, the friction-wheel rigidly connected with the spool, a main shaft on which they are mounted and adapted to revolve, a clutch feathered upon such main shaft, the cam-sector ec , the yoke-arm carrying a shaft on which is mounted the cam-sector, and a weighted arm for actuating the same, substantially as described.

3. In a clutch mechanism, an arm supported upon a main frame carrying a tripping-lever, with a latch pivoted at one end and adapted to

engage with a latch-pin attached to a cam-sector and to be tripped by the mechanism of a weighted arm mounted on the same shaft as the cam, substantially as described.

4. In a clutch mechanism, the cap hb , secured to the main frame and recessed to admit the flange of a collar rigidly connected with the rope-spool for holding the latter in the same relative position with the frame, substantially as described.

5. In a clutch mechanism, the combination of the yoke-arm ya , the shaft p , the weighted arm ta , the cam ec , the friction-wheel Fw , connected with the spool, a main shaft, and a supporting-frame, substantially as described.

6. In a clutch mechanism, a cam mounted on an axis supported in bearings above the main frame and adapted to control the forward and reverse movements of the clutches by its grip upon the face of a friction-wheel connected to the spool and mounted on the main shaft, substantially as described.

7. In combination with a clutch feathered upon a main shaft, a corresponding clutch connected with a friction-wheel and rope-spool and adapted to revolve on the main shaft, a cam for controlling the forward and reverse movement of the clutches by contact with such friction-wheel, and means for engaging and releasing the clutches, substantially as described.

8. In a clutch mechanism, the combination of a secondary frame above the main frame carrying a shaft in bearings, a cam-sector secured to and revolving with such shaft and adapted to engage with a friction-wheel mounted on the main shaft, one of the supports or standards of such secondary frame being loosely connected with the main frame by a set-screw or its equivalent to allow vertical motion for gaging and determining the frictional bearing of the cam on the friction-wheel, substantially as described.

9. In a clutch mechanism, a cam-sector mounted on a shaft in bearings above the main frame and adapted to engage the face of a friction-wheel mounted on the main shaft, the cam and its supports, capable of a vertical adjustment to determine its grip upon the friction-wheel, substantially as described.

10. In a clutch mechanism, the clutch c , having an opening dovetailed on one side to receive the diagonal arm of the steel face Sp' , in combination with such steel face, and a screw driven through the clutch and parallel with the face Sp' , and through the point of the diagonal arm, for holding the latter in place, substantially as described.

In witness whereof I have hereto set my hand this 20th day of April, 1883.

JOHN S. METCALF.
